UNITED STATES PATENT OFFICE.

GEORGE P. YOUMANS, OF GALESBURG, MICHIGAN, ASSIGNEE TO KALAMAZOO TANK & SILO COMPANY, OF KALAMAZOO, MICHIGAN.

WALL STRUCTURE.

1,336,179.

Specification of Letters Patent.

Patented Apr. 6, 1920.

Application filed July 25, 1918. Serial No. 246,673.

To all whom it may concern:

Be it known that I, GEORGE P. YOUMANS, a citizen of the United States, residing at Galesburg, in the county of Kalamazoo and 5 State of Michigan, have invented certain new and useful Improvements in Wall Structures, of which the following is a specification.

This invention relates to improvements 10 in wall structures.

The main objects of this invention are:

First, to provide an improved circular 15 wall structure having considerable height such as a silo, built of relatively short wood staves and one which is very rigid, strong and durable.

Second, to provide an improved wall 20 structure formed of wood staves, in which the joints of the structure are effectively protected from exterior moisture.

Further objects, and objects relating to 25 structural details, will definitely appear from the detailed description to follow.

I accomplish the objects of my invention 30 by the devices and means described in the following specification. The invention is clearly defined and pointed out in the claims.

A structure which is a preferred embodiment 35 of my invention is clearly illustrated in the accompanying drawing forming a part of this specification, in which:

Figure I is a front elevation of a silo embodying the features of my invention.

Fig. II is an enlarged detail with the 40 hoops omitted showing details of the arrangement of the staves.

Fig. III is a similar detail showing the manner of starting the wall.

Fig. IV is a detail vertical section on a line corresponding to line 4—4 of Fig. II, showing details of the hoop channels.

Fig. V is a detail vertical section on a line corresponding to line 5—5 of Fig. II, 45 showing one of the intermediate hoop channels.

Fig. VI is a detail section similar to that of Fig. IV showing a slight modification.

In the drawing, similar reference characters 50 refer to similar parts throughout the several views, and the sectional views are taken looking in the direction of the little arrows at the ends of the section lines.

Referring to the drawing 1 represents the base of a silo, 2 the roof and 3 a series of 55 doors. These parts are shown conventionally. The staves 4 are preferably five or six feet in length although this may be considerably varied as desired. The staves in the structure illustrated are arranged in half 60 lapping courses with their ends abutting and in starting and finishing the wall I employ half-length staves 5. When the staves are disposed in half lapping courses each 65 stave is provided at the center with a transverse hoop channel 6 which is preferably deepest at its edges, providing a central bead 7. Each stave has a rabbet-like recess 8 at each end which coact with the recesses of abutting staves to provide hoop channels alined with the channels 6, thus forming 70 continuous channels around the wall for the hoops 9. These hoops are preferably channel-shaped in cross section as shown in Figs. IV and V, and are disposed to embrace 75 the beads 7.

The upper edges 10 of the channels are preferably undercut providing drip ledges 11, while the lower edges 12 of the channels are outwardly inclined so that the water 80 runs or drains freely therefrom. The hoops being channel-shaped bind or engage only at their edges so that very perfect joints are formed between the hoops and the bottoms of the channel.

In the modification shown in Fig. VI the hoop 13 is rectangular in form, the bead being also rectangular.

With this arrangement of parts I provide a joint which effectively excludes the moisture and at the same time am enabled to use short wood staves in erecting circular wall structures, which when erected are very strong and rigid and durable and are economical to construct. The channels are preferably of such depth that the hoops lie entirely within the channels but the structure is very satisfactory if this feature is not present.

I have illustrated and described my improvements in the embodiment preferred by me. I am aware that very considerable variation is possible and satisfactory results still be secured. I have not attempted to illustrate or describe such variations as I believe the disclosure made will enable those

skilled in the art to which my invention relates to embody or adapt the same as may be desired.

Having thus described my invention, what I claim as new and desire to secure by Letters Patent, is:

1. A cylindrical wall structure comprising staves laid in half lapping courses with their ends abutting and having transverse 10 central hoop channels and rabbet-like end recesses coacting to form hoop channels alined with said central channels, the channels being deepest at their edges providing beads within the channels, the upper edges 15 of the channels being under cut providing drip ledges, the lower edges of the channels being outwardly inclined, and channel-shaped hoops disposed in said channels to embrace said beads, the depth of the channels being such that the hoops lie within the 20 plane of the surface of the wall.
2. A cylindrical wall structure comprising staves laid in half lapping courses with their ends abutting and having transverse 25 central hoop channels and rabbet-like end recesses coacting to form hoop channels alined with said central channels, the channels being deepest at their edges providing beads within the channels, and channel-shaped 30 hoops disposed in said channels to embrace said beads, the depth of the channels being such that the hoops lie within the plane of the surface of the wall.
3. A cylindrical wall structure comprising staves laid in half lapping courses with their ends abutting and having transverse 35 central hoop channels and rabbet-like end recesses coacting to form hoop channels alined with said central channels, the upper 40 edges of the channels being under-cut providing drip ledges, the lower edges of the channels being outwardly inclined and hoops disposed in said channels, the depth of the channels being such that the hoops lie within 45 the plane of the surface of the wall.
4. A cylindrical wall structure comprising staves laid in half lapping courses with their ends abutting and having transverse 50 central hoop channels and rabbet-like end recesses coacting to form hoop channels alined with said central channels, and hoops disposed in said channels, the depth of the channels being such that the hoops lie within the plane of the surface of the wall.
5. A cylindrical wall structure comprising staves laid in interlapping courses and having intermediate channel grooves alined with the joints of abutting staves and rabbet-like 55 end recesses coacting to form hoop channels alined with said intermediate channels of

adjacent staves, the channels being deepest at their edges providing beads within the channels, and channel - shaped hoops disposed in said channels to embrace said beads therein.

65

6. A cylindrical wall structure comprising staves laid in interlapping courses and having intermediate channel grooves alined with the joints of abutting staves and rabbet-like end recesses coacting to form hoop channels 70 alined with said intermediate channels of adjacent staves, and hoops disposed in said channels.

7. A cylindrical wall structure comprising staves laid with their ends abutting and having end recesses coacting to form hoop channels having a bead at the joint, the upper edges of the channels being under-cut providing drip ledges, their lower edges being outwardly inclined, and channel - shaped 80 hoops disposed in said channels to embrace said beads therein, the depth of the channels being such that the loops lie within the plane of the surface of the wall.

75

8. A cylindrical wall structure comprising staves laid with their ends abutting and having end recesses coacting to form hoop channels having a bead at the joint, and channel-shaped hoops disposed in said channels to embrace said beads therein, the depth of the 90 channels being such that the hoops lie within the plane of the surface of the wall.

85

9. A cylindrical wall structure comprising staves laid with their ends abutting and having end recesses coacting to form hoop channels, the upper edges of the channels being under-cut providing drip ledges, their lower edges being outwardly inclined, and hoops 95 disposed in said channels.

95

10. A cylindrical wall structure comprising staves laid with their ends abutting and having end recesses coacting to form hoop channels, the upper edges of the channels being under-cut providing drip ledges, and hoops disposed in said channels.

100

11. A cylindrical wall structure comprising staves laid with their ends abutting and having end recesses opening into each other and coacting to form hoop channels, and hoops disposed in said channels the depth of the channels being such that the hoops lie within the plane of the surface of the wall.

105

In witness whereof, I have hereunto set my hand and seal in the presence of two witnesses.

GEORGE P. YOUNMANS. [L.S.].
